(57) **CLAIM**

The ornamental design for a corn removal device, as shown and described.

DESCRIPTION

FIG. 1 is a perspective view of a corn removal device.

FIG. 2 is a front view of the corn removal device of FIG. 1.

FIG. 3 is a back view of the corn removal device of FIG. 1.

FIG. 4 is a side view of the corn removal device of FIG. 1.

FIG. 5 is another side view of the corn removal device of FIG. 1.

FIG. 6 is a top view of the corn removal device of FIG. 1; and, FIG. 7 is a bottom view of the corn removal device of FIG. 1.

The surface shading illustrated in the drawings is provided merely to highlight the contour of design; it is not intended to be illustrative of texture or gloss.

The broken lines showing the handle are for illustrative purposes only and form no part of the claimed design.
